UNITED STATES PATENT OFFICE.

LEOPOLD PLOM, OF RETINNE, AND JULIEN D'ANDRIMONT, OF LIEGE,
BELGIUM.

REAMER FOR FORMING BLAST-HOLES.

SPECIFICATION forming part of Letters Patent No. 399,156, dated March 5, 1889.

Application filed October 31, 1888. Serial No. 289,588. (No model.) Patented in Belgium December 23, 1886, No. 5,616; in France January 3, 1887, No. 167,827; in Luxemburg January 3, 1887, No. 783, and in England January 4, 1887, No. 129.

To all whom it may concern:

Be it known that we, LEOPOLD PLOM, of Retinne, and JULIEN D'ANDRIMONT, of Liege, Belgium, subjects of the King of Belgium, have invented certain new and useful Improvements in Reamers for Forming Blast-Holes, (the same having been patented in the following countries, to wit: In Belgium December 23, 1886, No. 5,616; in France January 3, 1887, No. 167,827; in Great Britain January 4, 1887, No. 129, and in Luxemburg January 3, 1887, No. 783.) of which the following is a specification.

Our invention is a device for blasting coal and other minerals; and it relates to devices employed in the mode of blasting where an inner enlarged cavity is formed communicating with an ordinary bore-hole for the purpose of breaking away a greater amount of the mineral at a single operation, as fully described in our copending application, Serial No. 225,495, filed January 25, 1887. It will be understood upon reference to said application that the bore-hole is extended a distance beyond the enlarged cavity and a plug then inserted in such a manner that the force of the explosion is not exerted upon the plug longitudinally to drive the same from its position. With the above ends in view our invention consists in providing a suitable tube having diametrically-opposite slots, with a stem having pivoted to its ends two serrated or other boring arms or wings, so shaped that when the stem is inserted in the tube a sufficient distance and then withdrawn slightly the wings will engage the forward extremities of the slots and be forced outward transversely to the tube, when the tube may be rotated to cut away the desired cavity, the wings being continually extended laterally by the continued movement of the stem. Forward of the cutting-wings the stem may be formed into a helical screw for engaging and discharging forwardly the dust or material cut away in the cavity. Just above the surface suitable apertures or slots may be formed in the tube to permit the escape of the finely

divided mineral. To afford means for movement of the stem with its wings relatively to its containing-tube, a suitable sleeve is formed on the upper end of the tube having internal screw-threads, and a correspondingly-screw-threaded head is formed on the stem which adapts it to engage in said sleeve, and when the latter is turned to effect the relative movement between the two parts.

In order that our invention may be fully understood, we will proceed to describe the same with reference to the accompanying drawings, and then particularly point out the novel features in the claims.

In said drawings, Figure I is an axial section of the preferred form of our device, showing the arms or wings extended. Fig. II is a similar view of the lower end of the device, showing the arms or wings folded. Fig. III is a section taken through a strata of the mineral to be operated upon, showing the bore-hole, enlarged cavity, plug, fuse, and tamping in position, as fully described in our herein-before-referred to application.

We will state here that we do not claim the method (shown in Fig. III) of blasting, but have claimed the same in the prior application.

A represents the arms or wings, pivoted on the stem C and having serrations a, said arms and stem being inserted in the tube D. The stem C has the helical conveyer D, for the purpose of forwarding the granulated or pulverized material. s g are slots, respectively, for the spreading of the arms and the outlet of material.

F is a sleeve keyed at i i to the tube D in such a manner that it may be rotated thereon without moving longitudinally. This sleeve D has screw-threads f, in which engage corresponding threads, l, on the head L of the stem. This stem C may have a square head, c, for the reception of a hand wheel or crank, X, for turning the stem with its wings, and, by means of the engagement of the latter with the sides of the slots, the tube.

In practice a hole, H, is bored into the mineral to be blasted, the tube D, with the stem

and wings in the position shown in Fig. II, then inserted to the proper depth, a crank applied to the end C for rotating the stem, and, by means of the wings, the tube with it, the 5 sleeve F slowly rotated to move the stem C outward, whereby the wings A will be gradually extended, the rotation of the whole being constantly kept up and the cavity M thereby formed. While this operation is going on 10 the minute particles will enter through the slots s, gradually work upward until they reach the conveyer B, when they will be forwarded to the slots g outside of the bore-hole and be deposited upon the ground. To withdraw 15 the instrument, the rotation of the sleeve F is reversed until the head L reaches the inner end of the sleeve, when the wings will be found to have reached the folded position and the tube may be easily withdrawn.

20 This device, it will be seen, is a ready and effective instrument for performing the work hereinbefore described, but it may be varied in minor details. The manner in which the sleeve F is keyed to the tube D may be varied 25 at will; also the means for rotating the whole instrument in the hole, and the sleeve F may be provided with suitable means whereby it may be more readily rotated upon the tube.

It will be noticed that the tube is provided 30 with two pairs of slots, through either one of which the wings may be extended. Of course we do not limit ourselves to four slots, or any number, for, if desirable, three or even more pairs may be used; or, if necessary for the sake of strength, one pair only may be used.

As hereinbefore stated, we do not claim in 35 this application the method of blasting, but simply the instrument, hereinbefore described, whereby the inner cavity may be produced.

40 Having thus fully described our invention and the manner in which the same is to be operated, the following is what we claim as new therein and desire to secure by Letters Patent:

45 1. In an instrument for forming blast-holes in coal or other mineral, the combination, with an inclosing-tube and a drill-rod having an extensible end folding within said rod, of a sleeve screwing on one end of the above 50 members and secured to the other, so as to rotate thereon, whereby the latter may be

withdrawn substantially in the manner explained.

2. In an instrument for forming blast-holes, the combination, with the tube D, having apertures s, of a rod, C, located within said open-ended tube and having the wings A pivoted to it, said wings being inclined outward, whereby they engage in the apertures when moved in one direction and fold upon the rod, 60 and are brought entirely within the tube when moved in the other direction, substantially as herein explained.

3. In an instrument for forming blast-holes, substantially as described, the combination, 65 with the tube D, having apertures g, of the rod C, carried by the tube and having a cutting end, and a spiral portion, B, for conveying the pulverized material from the cutting end and discharging it through the apertures 70 g, substantially in the manner explained.

4. In an instrument for forming blast-holes, substantially as described, the combination, with the tube D, having sleeve F, keyed by a lug and annular slot thereon, of a rod, C, having 75 wings A bent outward in opposite directions, whereby they engage an edge on the tube and a head, L, said sleeve and head having corresponding screw-threads, whereby upon rotation of the sleeve the rod is moved relatively 80 to the tube D and the wings A extended, as fully explained.

5. In an instrument for forming blast-holes, substantially as described, the combination, with the tube D, stem C, and wings A, mounted 85 on the stem, said tube having the apertures s g, and the sleeve F, keyed thereon so as to be rotatable, of a rod having the conveyer B and head L and crank X, said head and sleeve F being correspondingly screw-threaded, whereby they engage, and upon rotation 90 of the sleeve the rod is moved relatively to the tube to extend the wings and convey the fine material to discharge it through the apertures g, the whole instrument being rotated 95 substantially in the manner herein set forth.

LEOPOLD PLOM.
JULIEN D'ANDRIMONT.

In presence of—

WM. S. PRESTON,
M. DE MATHELIN.

Correction in Letters Patent No. 399,156.

It is hereby certified that in Letters Patent No. 399,156, granted March 5, 1889, upon the application of Leopold Plom, of Retinne, and Julien D'Andrimont, of Liege, France, for an improvement in "Reamers for Forming Blast-Holes," an error appears in the printed specification requiring correction, as follows: In lines 56-7, page 2, the compound word "open-ended" should be stricken out and inserted in line 55, same page, before the word "tube;" and that the Letters Patent should be read with this correction therein that the same may conform to the record of the case in the Patent Office.

Signed, countersigned, and sealed this 12th day of March, A. D. 1889.

[SEAL.]

D. L. HAWKINS,

Assistant Secretary of the Interior.

Countersigned:

BENTON J. HALL,

Commissioner of Patents.
